UNITED STATES PATENT OFFICE.

CARL F. BRAUN, OF SAN FRANCISCO, CALIFORNIA.

EVAPORATOR AND METHOD OF OPERATION.

Application filed March 14, 1922. Serial No. 543,584.

This invention relates to an evaporator and particularly pertains to apparatus for bringing about the distillation of liquids.

In the petroleum industry at the present time it is common practice to bring about the distillation of hydrocarbon liquids by the use of horizontal stills in which the liquid is placed, and where distillation is brought about by the exterior application of heat or the delivery of steam to the body of liquid and at the bottom thereof. In either instance it has been found difficult when the liquids are at substantially the same boiling point to insure that the various fractions of distillate may be carried off from the liquid without the possibility of recondensing the fractions and causing them to be again absorbed by the remaining body of undistilled liquid. It is the principal object of the present invention, therefore, to provide an evaporator or still, within which hydrocarbon liquids may be readily evaporated by a method which will insure that there will be a maximum progressive distillation of the various fractions of oil, and at the same time a minimum condensation of the fractions after distillation.

The present invention contemplates the use of a vertical still to which a liquid and a fluid may be delivered and heated, at which time a condition of partial pressure will be created at the evaporating surface of the liquid, the invention further having in mind a counter circulation of the fluid and liquid in different paths of travel, whereby condensate and other particles of liquid in suspension will not be carried from the still.

The invention is illustrated by way of example in the accompanying drawings, in which:

Fig. 1 is an enlarged view in central vertical section through the still with which the present invention is concerned, a portion of said still being broken away for the sake of convenience.

Fig. 2 is an enlarged transverse section through the still on the line 2-2 of Fig. 1.

Referring more particularly to the drawing, 10 indicates a tubular vertical shell preferably cylindrical in section. The lower end of this shell is formed with a bolting flange 11 adapted to receive bolts 13 which pass through a flange 14 formed as a part of a cover cap 15. The upper end of

the shell is formed with an enlarged circumscribing wall portion 16 by which a semi-circular vapor outlet channel 17 and a semi-circular oil inlet channel are provided. The upper end of the shell 10 terminates a distance short of the wall portion 16, thus forming an annular opening establishing communication with the central passageway through the body of the shell. The terminating end of the wall 16 agrees in configuration and alignment with the main body of the shell and is fitted with a flange 19 to receive bolts 20. These bolts pass through flanges 21 of a dome 22. This dome is provided with a fluid inlet opening 23. The upper end of the dome is fitted with a cover plate 24 secured in position by bolts 25 which pass through flanges 26 and 27 of the plate and the dome respectively. Suitable packing means 28 are interposed between the body of the dome and the cover plate.

Suspended from the top of the shell is a tube nest 29. This nest of tubes is provided with an upper tube sheet 30 which is clamped between the upper end of the shell and the lower face of the dome. Suitable packing washers 31 are used to prevent leakage in the joints between the various members. A plurality of tubes 32 pass through the tube sheet and extend downwardly to pass through a lower floating tube sheet 33. This sheet is fitted with a cap 34 held in place by bolts 35 and forming a condensate chamber 36. Attention is directed to the fact that the outside diameter of the tube sheet 33 and the cap 34 are somewhat smaller than the inside diameter of the cap member 15, thus making it possible for the tube nest to freely float at its lower end and to adjust itself as expansion and contraction takes place in its members.

A condensate drain pipe 37 connects with the bottom of the cap 34 and extends downwardly through the shell cap 15. This pipe is free to move longitudinally, a tight joint being made between the shell cap and the pipe by a stuffing box 38.

The oil inlet chamber 18 formed around the upper end of the shell body receives a constant supply of oil through an inlet connection 39 as more clearly shown in Fig. 2. This oil is delivered to the central shell chamber through a plurality of nozzles 40. These nozzles extend radially through the

side walls 16 and 10 of the shell and are removably secured in the shell by an outer threaded portion 41. Inlet openings 42 are formed through the upper wall portions of each nozzle, to permit the oil to drain from the compartment 18 into the nozzle and to thus pass into the innermost ends of the nozzles. The oil delivered to the shell chamber through the nozzle flows directly into a baffle pan 43. By reference to Fig. 1 it will be seen that a plurality of baffle pans are used, one substantially agreeing in outside diameter with the inside diameter of the shell as indicated at 43, and pans 44 of much smaller diameter, but larger than the outside sectional dimensions of the tube nest. The tubes 32 pass successively through alternate pans 43 and 44, which pans act as distributing chambers for the oil and as baffles for a vapor or gas circulating upwardly through the shell. The openings provided in the floor of the pans for the tubes 32 are of somewhat larger diameter than the tubes as indicated at 45, thus insuring that a film of oil will be uniformly created around the outer surface of each of the tubes, said film flowing downwardly along the tubes and through the floors of the various pans. Attention is directed to the fact that one or more pans may be disposed above the point of entry of the oil to serve as baffle members and to prevent particles of oil from passing directly from the shell.

In operation of the present invention, oil is delivered to the upper end of the shell through the inlet pipe 39, after which it flows into the semi-circular passageway 18 and then flows through the main wall of the shell through the nozzles 40. These nozzles feed the oil into a pan 43. This pan will gradually fill up as determined by the rate of flow of the incoming oil. The oil will gradually distribute itself over the floor of the pan and will encounter the surface of the tubes 32.

Due to the fact that there is a small annular passageway 45 formed around each of the tubes, a thin film of oil will be applied to the entire cylindrical face of each tube. This oil will gravitate along the tubes toward the bottom of the shell. While this passage of oil is taking place, fluids are flowing in counter directions through the tubes and around the tubes. The temperature of the fluid within the tube must be greater than the temperature of the fluid flowing around the tube, thus preventing the possibility of condensation of the surrounding fluid from taking place on the tubes. At the same time this will insure that the thin film of oil which is flowing down the tubes will be directly heated through the wall of the tubes by the downwardly flowing fluid in the tubes.

The flowing oil will be in constant contact

with a heating surface while being maintained in a thin film and at the same time this oil will present an evaporation surface which is acted upon by the upward flowing fluid surrounding the tubes, and which fluid is flowing along a definite path of travel and in a counter direction to the flow of oil. This upwardly flowing fluid which is in most instances steam, is not miscible with oil in all proportions and at the boiling point of the mixture the sum of the vapor pressures of the two constituents must be equal to the total pressure, while the liquid is boiling. The boiling point must therefore be lower than that at ordinary pressure of the two substances because the partial pressure is necessarily smaller than the total pressure which is equal to that of the atmosphere.

By examining the section of applicant's still it will be noted that due to the laws of partial pressure distillation will be progressively carried on at diminished pressures so that volatilization of the different fractions in the series represented by the oil being passed through the still will take place as certain points are reached by the oil in its downward travel. Thus there will be a varying condition of partial pressure and vapor tension throughout the length of the still and the various successively heavier fractions will pass off as the oil flows towards the bottom of the still while it is moving into a zone having an atmosphere of practically pure steam approaching the steam inlet pipe and while it is continuously flowing along the heated pipes 32. Due to this arrangement there will be progressive volatilization of the oil, progressive exposure of the oil to the upflowing steam and progressive operation of the various fractions from the oil as the oil flows downwardly.

It will be further noted that as the oil continues its flow toward the bottom of the still a quantity of residuum will accumulate. This material will be directly acted upon by the inflowing steam, thus insuring that all possible fractions will pass off from the oil in vapor form. Condensation of the steam may take place in the member 34 and may be drained off through the pipe 37. Expansion of the tube nest will be compensated for by the sliding joint indicated at 38.

While I have shown the preferred form of my invention as now known to me, it will be understood that various changes in the combination, construction and arrangement of parts may be made, by those skilled in the art, without departing from the spirit of my invention as claimed.

Having thus described my invention, what I claim and desire to secure by Letters Patent is:

A method of distillation in a still con-

sisting of an outer vertically disposed shell down through which a plurality of tubes extend, which consists in creating an upward flow of steam in the shell and around the tubes, simultaneously internally heating the walls of the tubes, by flowing hot oil downwardly therethrough to maintain a surface temperature on the walls of the tubes higher than that of the steam in the shell throughout their length and flowing thin ¹⁰ films of oil on the outer surfaces of the tubes, to distill the same.

CARL F. BRAUN.
